TANK SHIP BULKHEAD AND GIRDER CONSTRUCTION

Vincent Albiach, Paris, France

Application August 24, 1951, Serial No. 243,463

4 Claims. (Cl. 114—79)

The instant invention relates to ship construction, and particularly to an improved tanker.

Among all the types of merchant ships, those vessels intended for the transportation of petroleum or other liquids in bulk are particularly affected by conditions at sea. The reasons for placing the oil tanker in this particular category are threefold.

In the first place, tankers are generally designed to navigate at the minimum freeboard permitted by the International Convention Tables on Load Lines. To this end the superstructure is reduced to a minimum, and therefore its contribution to the strength of the hull structure is correspondingly reduced. Secondly, the propelling installation is generally arranged aft, and seldom amidship as is the case for the majority of other types of ships. This results in an increase of the loading of a tanker in the order of 15%, by comparison with a cargo ship of the same hullform but with the engines amidship. Finally, the nature of the cargo creates special problems. The petroleum cargo, which may not be evenly distributed especially when the ship is in a ballast condition, imposes local loads on certain parts of the hull structure such as the longitudinal and transverse bulkhead platings, the motion of the ship at sea causing inertial forces to be exerted upon the hull.

In the past, tankers have been designed with the object of integrating the longitudinal bulkhead platings into the main structure of the ship so as to provide added stiffening against the main hull stresses imposed by hogging and sagging while the ship is under way. The liquid cargo exerts hydrostatic stresses (static and dynamic) upon the ship's hull so that these stresses had to be algebraically added to the hogging and sagging stresses in calculating the scantlings for the various members of the hull structure. The superposition of these stresses on the longitudinal bulkhead platings frequently resulted in fractures, with the concomitant dangerous possibility of their spreading to adjoining structural elements.

The present invention avoids this superposition of stresses on the longitudinal bulkheads, these bulkhead platings being so constructed that they are in effect "filling panels" and hence need only be designed to withstand the hydrostatic stresses imposed by the liquid cargo.

In accordance with the present invention, the longitudinal bulkhead platings are composed of sections positioned between reinforced keelsons at the ship's bottom and reinforced continuous girders at the top side, the sections of the bulkhead being interposed between cruciform struts arranged as pillar members in the region of the transverse bulkhead platings. In the preferred form of the invention, the longitudinal bulkhead platings are formed from flanged plates in U-form so as to have vertical corrugations. The resulting fluted form of the bulkhead plating has a taper varying linearly from the bottom to the top in accordance with the moment of inertia of horizontal sections thereof, adjusted to the stresses of the liquid cargo.

The new construction reduces the possibility of frac-

2

tures in the hull structure by avoiding the superposition of the hull stress and the hydrostatic stresses characteristic of prior art designs. Also, it facilitates prefabrication and repair, thus lowering both the initial shipbuilding costs and the costs of maintenance while the tanker is in service.

A better understanding of the invention may be had from the following description taken in conjunction with the accompanying drawings, in which:

10 Fig. 1 is a reinforced transverse half section in accordance with the invention, taken along the line 1—1 of a longitudinal bulkhead plating shown in Fig. 3, the port and starboard half sections being identical.

Fig. 2 is an ordinary transverse half section in accordance with the invention, taken along the line 2—2 of a longitudinal bulkhead plating shown in Fig. 3, the port and starboard half sections being identical.

Fig. 3 is a horizontal section in accordance with the instant invention taken on a reduced scale along the line 3—3 of a longitudinal bulkhead plating shown in Fig. 1.

Fig. 4 is a horizontal section, also on a reduced scale, of another embodiment of a longitudinal bulkhead plating.

Fig. 5 is a perspective view of a longitudinal bulkhead plating in accordance with the instant invention.

Fig. 6 is a diagrammatic horizontal sectional view, on a reduced scale, as seen from about the level of the line 3—3 in Fig. 1.

Referring to the drawings, the tanker comprises two longitudinal bulkhead platings 25 (Figs. 1 and 2), running fore and aft and dividing the cargo portion of the ship into three sections. A number of transverse bulkhead platings 26 (Fig. 3), placed perpendicular to the longitudinal bulkhead platings, subdivide these longitudinal sections into tanks, the outboard tanks being called wing tanks (one on the port and one on the starboard side), and the inner tank being called a center tank. Between successive transverse bulkhead platings, the ship's hull comprises reinforced and ordinary sections, as shown in Figs. 1 and 2, respectively.

Referring now to Fig. 1, there is shown a reinforced section of a tanker in accordance with the invention. The hull is bounded by a bottom 1, deck 2 and shell 3. In order to help stiffen the ship's girder against fore and aft deflection, longitudinals 4, 5 are provided at the bottom and at the deck, respectively. Under the deck 2, a continuous deck transverse 6 is arranged, and similarly at the bottom 1 a continuous bottom transverse 7 is positioned in the port to starboard direction. A reinforced frame 8 is mounted between the deck and bottom transverses 6, 7. Added strength is provided for the hull structure by diagonal ties 9, 10. Diagonal tie 9 is secured between lugs 11 and 12, which are integrated with the reinforced frame 8 and the deck transverse 6, respectively. Similarly, diagonal tie 10 is mounted between lugs 13 and 14 integrated with the reinforced frame 8 and the bottom transverse 7, respectively. At the outboard ends of the diagonal ties 9 and 10, stiffeners 15 are secured to the frame 8 and shell 3, while at the inboard ends, stiffeners 16 and 17 are fastened, respectively, to deck transverse 6 and bottom transverse 7.

Under the deck 2 and on the ship's center line is a continuous longitudinal center line girder, shown generally at 18. The vertical center keelson 19, running fore and aft, is positioned on the center line at the bottom of the hull, and is reinforced by a bracket 21 and a flat plate 20.

Near each side of the ship, a side keelson 22 is provided as added longitudinal stiffening for the bottom 1. Each side keelson 22 is reinforced by a flat plate 23. Under the deck and in vertical alignment with each side keelson 22, a continuous girder 24 is similarly pro-

vided as added longitudinal stiffening at each side of the deck, girders 24 being reinforced by plates 24a.

As previously stated, the two longitudinal bulk-head platings 25 partition the ship's breadth into three sections or rows, each bulkhead plating 25 being erected between the reinforced side keelson 22 at the bottom and the continuous reinforced girder 24 at the top. In accordance with the invention, the longitudinal bulkhead platings 25 are formed by means of flanged plates in U-form so as to have vertical corrugations, as shown in Figs. 3, 4 and 5. The flanged plates may be placed butt to butt as in Fig. 3 or overlapped as in Fig. 4.

The corrugated bulkhead platings 25 are tapered, varying linearly from the bottom at plate 23 to the top under plate 24a. This is best illustrated in the perspective view shown in Fig. 5, where it will be observed that dimension c at the foot is greater than the length b shown at the top.

The longitudinal bulkhead plating 25 is not continuous but terminates just short of a transverse bulkhead plating 26 (Figs. 3 and 4) so as to form sections 25 between successive transverse bulkhead platings. Between the terminations of the corrugated bulkhead platings 25 on each side of the transverse bulkhead plating 26, cruciform struts 27 extend vertically so as to form a strong pillaring member between the deck and bottom portions of the ship. As shown in the drawings, particularly Figs. 3, 4 and 6, these struts 27 form the intersections of the longitudinal bulkhead plating 25 and the transverse bulkhead plating 26, the struts having arms 27a secured to these bulkhead platings in substantially liquid-tight relation, to complete the liquid cargo tanks.

Referring now to the transverse section illustrated in Fig. 2, this section comprises side stringers 29 extending fore and aft along the side of the hull, the stringers 29 having brackets 31. Between the deck and top stringer, a stiffening plate 30 is mounted. The bottom longitudinals 4 are secured by transverse stiffener 32. The vertical center keelson 19 is strengthened in this section by a vertical stiffener 34. The girder 24 and side keelson 22 are reinforced by brackets 35 and 33, respectively.

When a ship is underway at sea, the hull girder is subjected to bending stresses imposed by the conditions of hogging and sagging. The terms "hogging" and "sagging" are used to refer to the two opposed conditions of longitudinal deflection of the ship's girder. In the sagging condition, the deflection is downward in the region of midship, while in the hogging condition the deflection is upward in this region. Various combinations of hog and sag can and do, of course, occur under dynamic conditions at sea.

In prior art designs, the longitudinal bulkhead platings are integrated into the main structure of the ship so that they cooperate in resisting the bending moments imposed by hog and sag. In a tanker, the longitudinal bulkhead platings are also subjected to the static and dynamic hydrostatic stresses of the liquid cargo, the motion of the ship under way causing inertial forces to be exerted. Thus, there results a superposition of the main hull stresses (bending moments due to hogging and sagging) and the local stresses (hydrostatic stresses), a combination which is the cause of a large number of fractures in the ship's structure. The most serious consequence of these fractures is the danger of their spreading to parts of the adjoining structures, especially where the ship is of welded construction as is the case in most modern tankers.

I have found it advantageous to avoid this superposition of the main hull and local stresses. According to my invention, the cruciform struts 27 at the intersections of the longitudinal and vertical bulkhead platings 25, 26 serve as pillaring members so as to cooperate with the ship's girder in resisting the main hull stresses. The longitudi-

nal bulkhead platings 25 thus act as "filling panels" between the above-described members and hence are only required to sustain the local stresses. Accordingly these bulkhead platings may be designed with scantlings having a reduced margin sufficient only to support the hydrostatic loads due to the liquid cargo, thus effecting valuable savings in the weight of the ship.

Another advantage of the invention over the prior structures stems from the tapered fluted form of the bulkhead plating 25 (Fig. 5). This configuration enables one to adjust the moment of inertia of different horizontal sections of the bulkhead plating to the stresses transmitted by the liquid cargo, so that further savings in weight can be obtained.

The new construction also facilitates prefabrication and makes cleaning and maintenance in service much easier. The flanged plates for the corrugated longitudinal bulkhead platings 25 may be lowered into the hold, so that construction of the main ship structure can proceed independently. Similarly, when repairs are required in the longitudinal bulkhead plating, sections of it may be removed with a minimum of disturbance to the remaining ship's structure.

I claim:

1. In a tanker ship having a shell, bottom and deck, the combination of a center keelson extending longitudinally along said bottom, side keelsons extending longitudinally along said bottom, one on each side of the center keelson, continuous girders under the deck and in vertical alignment with the respective side keelsons, bulkhead platings extending transversely of the girders and side keelsons, longitudinal bulkhead plating mounted directly above and below and secured in substantially liquid-tight relation to the side keelsons and deck girders, said longitudinal bulkhead plating terminating short of the transverse bulkhead plating, and cruciform struts forming the intersections of the bulkhead plating and extending vertically from the side keelsons to the deck girders and secured to said side keelsons and deck girders and having arms secured to said longitudinal and transverse bulkhead plating, all in substantially liquid-tight relation, the bulkhead plating forming with the struts a series of liquid cargo tanks, the struts constituting the main pillaring for the deck girders, thereby enabling the use of bulkhead plating of reduced scantling.

2. The combination according to claim 1, in which the longitudinal bulkhead platings are corrugated vertically.

3. The combination according to claim 1, in which the longitudinal bulkhead platings are corrugated vertically, the corrugations having greater depth at the bottom of the bulkhead platings than at the top thereof.

4. The combination according to claim 1, comprising also deck and bottom transverses, a reinforced frame mounted between said transverses adjacent the shell, and diagonal ties extending from said frame to the deck and bottom transverses, respectively, said ties terminating adjacent the vertical extremities of the longitudinal bulkhead platings.
